UNITED STATES PATENT OFFICE

CHARLES B. BARTLEY AND VIRGIL H. DAKE, OF PITTSBURGH, PENNSYLVANIA

CONTROL SYSTEM

Application filed March 19, 1928. Serial No. 262,698.

Our invention relates to electro-magnetic devices and more particularly to the type usually termed relays.

Certain disadvantages are present in relays commonly employed in electric circuits generally. One disadvantage of the prior relays is the limited applicability of range of operation of a given type of relay. Another is the inherent inability to function properly, or general ineffectiveness and liability to damage when employed in circuits subject to widely varying current values, and the lack of sensitiveness and inability to respond to small current variations when used in connection with circuits carrying relatively heavy currents. Further disadvantages of prior relays are that the movement of relay parts may lag behind current changes to which the relay is intended to respond, and also they may become ineffective without any warning. These and other conditions necessitate choice, from among numerous types and designs of relays, of a particular relay for a specific duty.

The object of our invention generally stated is to provide an electro-magnetic device wherewith the movement of an armature is effected in response to predetermined changes in a plurality of magnetic fields.

It is also an object of our invention to provide in an electro-magnetic device for controlling the flux density of a magnetic field in such a way that the movement of an armature disposed in the field caused by change in the magnitude of the field may be accurately and positively predetermined.

A special object of the invention is to provide permeable means common to different magnetic fields for varying the effect of the magnetic fields upon an armature actuated by changes in said fields.

A further object of the invention is to provide a practical and dependable relay which may be adjusted to respond with as great sensitiveness and rapidity when employed in a circuit in which small current values are encountered, as it will when employed in circuits carrying currents of relatively large values, and which will not be easily destroyed

or rendered inoperative when relatively excessive currents are encountered.

A still further object of the invention is to provide a relay whose marginal adjustments permit a variation of the limits of the relay operation both in respect to the width of the margin and to the position of the margin with respect to the minimum and maximum current values for a particular capacity and design of relay.

Other objects of the invention are to provide a relay which is of simple, inexpensive and rugged construction, dependable in its operation, capable of rapid action, and whose adjustments are not readily disturbed, and which is as useful for registering changes in or controlling alternating current as it is for direct current.

The invention may be embodied in a relay comprising two spaced concentric solenoids which are adapted to carry currents of different values, a core disposed in the inner solenoid, and armature mounted longitudinally between the solenoids, and means for varying the density of the magnetic flux surrounding the solenoids for varying its effect upon the armature.

The invention is illustrated in the accompanying drawings, in which Figs. 1 and 2 are schematic, front and side elevational views respectively of a relay embodying our invention; Fig. 3 an end view looking upwardly at the lower ends of Figs. 1 and 2 with the pole pieces removed; Figs. 4, 5, and 6 schematic diagrams showing various circuit connections for the solenoid windings, and Fig. 7 a diagrammatic representation of a particular application of the relay. In the drawings, all framework, connecting members, and other parts not essential or forming a part of the invention have been omitted for simplicity of representation.

In accordance with the invention as embodied in the relay shown in the drawings, the outer solenoid 1, Figs. 1 to 3, comprises a coil of comparatively large low resistance current conducting wire capable of carrying with safety a current greatly in excess of that normally passing through the relay. Mounted concentric with, and disposed within the

solenoid 1 is an inner solenoid 2 comprising a number of turns of smaller and higher resistance current conducting wire, but which has a factor of safety for carrying an excessive current that is substantially the same as that of solenoid 1.

In order that the number of turns of the outer solenoid 1 included in a particular circuit may be varied, taps 3 are provided and connected to different points in the solenoid 1, and in order to increase the strength of the magnetic field set up by the inner solenoid 2, an iron core member 4 is inserted in the center of the solenoid. Disposed longitudinally between the two solenoids and pivotally supported at one end by a pin 6 passing through it and the core 4 is an armature 5, which is adapted to be actuated by the magnetic flux set up by the two solenoids. A spring 7 is provided to bias the free end of the armature 5 away from the longitudinal center of the inner solenoid to increase the length of the magnetic circuit.

The outer solenoid 1 normally has but small magnetic effect upon the armature 5 because of the distance between the two solenoids resulting in but a small portion of its magnetic flux passing through the armature and to definitely superimpose portions of the magnetic flux surrounding the solenoid 1, or for concentrating of it upon the armature 5 to control the operation of the armature, in the manner more specifically described hereinafter, the floating pole pieces 8 are provided and mounted near the free end of the armature in a manner (not shown) to allow for horizontal and vertical adjustment with reference to each other, to the solenoids 1 and 2 and to the armature 5. In this particular application, only two pole pieces are shown, but it will be quite evident to those skilled in the art that the number may be greatly varied. The pole pieces comprise material having high magnetic permeability characteristics, which may be employed in either its normally unmagnetized state or in a permanently magnetized state, as the design of instrument may require.

In order that an electric circuit may be made or interrupted when the armature 5 is moved from one position to another, a movable contact member 9 is mounted on the armature 5, and adapted to make engagement with a fixed contact member 11. Evidently, different types of contact devices may be used and different arrangements made where desired.

It is possible to make operable circuit connections for the solenoids in a number of various ways without departing from the invention. One example is illustrated in Fig. 4 where the outer solenoid 1 is connected in series circuit relation with the circuit to be controlled, and the inner solenoid 2 is short circuited upon itself. In a circuit connection

of this character as is well known, solenoid 2 will be energized only by transformer action making it particularly adaptable for alternating current circuits or for direct current circuits where the relay is employed for registering comparatively quick changes in current values.

Another example of a preferred circuit connection is that in which the outer solenoid 1 is shown connected in series circuit relation with the circuit to be controlled, and the inner solenoid 2 is connected to a constant source of supply, such as a battery 12, thus maintaining a normally substantially constant magnetic pull upon the armature 5 which may be readily varied merely by changing the applied voltage. In Fig. 6 the solenoids, as illustrated, are connected in parallel circuit relation to each other in the circuit to be controlled. Accordingly, the relative changes in magnetic field values of the two solenoids will be substantially constant. For most general purposes this latter connection has been found to be the preferred circuit connection.

When the device or relay is inserted in an electric circuit and the pole pieces 8 are disposed in their most inoperative position, the lines of flux set up by the outer solenoid 1 will mostly all be in air, because of the comparatively large diameter of that solenoid, spacing it at a substantial distance from the core 4 of the inner solenoid 2 and the armature 5. The magnetic flux surrounding the inner solenoid 2 when energized however will be practically all concentrated in the core member 4 and the armature 5, as in the ordinary relay, and as is well known the magnetic lines of force seek their path of lowest resistance, which in this instance is through the armature 5. Accordingly, the armature 5 is urged to a position to reduce the air gap between the armatures and the core 4 to a minimum. Hence by adjusting the tension in the spring 7, attached to the armature 5, to different values, the magnetic pull necessary to move the armature 5 can be predetermined, and as is also well known, the magnetic pull of a solenoid is proportional to the current flowing in the solenoids, it follows that the spring can be adjusted to predetermine the change in current necessary to effect movement of the armature 5.

In this invention, as referred to hereinbefore, the magnetic pole pieces 8 are provided for the purpose of superimposing part of the magnetic flux surrounding the outer solenoid upon the armature 5 to aid or oppose the movement of the armature, and it will be readily understood by those skilled in the art that by employing such means to cause the magnetic flux surrounding the outer solenoid which normally does not materially influence the armature 5 to either aid or repel the effort exerted on the armature 5 by the

inner solenoid 2, that much finer and more sensitive adjustment of the armature movement can be obtained. To more clearly understand the action of the relay, assume that the spring 7 has been adjusted to prevent movement of the armature 5 until a current of 10 amperes flows in the circuit to be controlled, and also assume that normally the magnetic field of the outer solenoid 1 does not materially affect the armature 5. It will be readily understood that by applying the flux produced by the outer solenoid 1 to the armature and magnetic field of the inner solenoid, an attracting or repelling force can be brought to bear thereon, which may cause movement of the armature when a current much less than 10 amperes is flowing in the main circuit, or else will not allow movement of the armature until a current of much more than 10 amperes flows in the main circuit, and the magnetic flux of the outer solenoid can be so controlled to affect the movement of the armature by the use of permeable magnetic pole pieces 8. The theory supporting this action is too well known to need explanation here.

To further amplify the above, by providing for moving the pole pieces 8 substantially freely in the fields as suggested, an infinite number of different practically positive adjustments of the relay can be accomplished. Each of the pole pieces 8 therefor is made independently adjustable so as to vary the magnetic flux influenced by it, and depending upon its situation in the field in relation to the outer solenoid 1 and the armature 5, each is capable of influencing the operation of the armature 5. This use of the pole pieces for directing the influence of the magnetic flux of the outer solenoid 1, as stated above, secures greater sensitivity of the relay since the added effect of the flux set up by the outer solenoid 1 can be varied at will by large or very small increments, depending upon the manner in which the pole pieces 8 are disposed in the magnetic field. When they are perpendicular to the core member 4 in their maximum inner position, they will influence a minimum number of flux lines from solenoid 1, and as they are moved outwardly and perpendicularly, the magnitude of the flux influenced by them will be greatly increased, and their effect upon the armature 5 is augmented. In addition to the above, by employing in the inner solenoid 2 a conductor of very high resistance together with an iron core 4 therefor, a very small and light armature 5 may be provided and adapted for movement in response to but very small changes in current value in the inner solenoid, but which changes may correspond however to very large changes in the current in the outer solenoid 2 depending upon the relative resistance values of the two solenoids. In ac-

cordance with the description directed to the function of the movable pole pieces, it follows that though the relay is adapted for use with very large currents, and as the inner solenoid 2 and armature 5 are practically isolated from harm caused by current change, they can be made to function properly for very small changes in current in the circuit to be controlled, or only for very large changes, depending upon the adjustment of the pole pieces. 70

The fact that the armature biasing means and the number of turns in the outer solenoid can be readily changed, also greatly multiplies the regulation and application of 80 the relay.

By employing a type of construction described hereinbefore, a relay may be provided which is adapted to operate effectively and safely in circuits where currents of but 85 a very few milliamperes are encountered, or in one where currents of the order of one hundred amperes are encountered, and its sensitivity can be readily controlled and varied in each application by adjustment of 90 the pole pieces 8. For example, it has been found that if but a very few milliamperes are flowing through solenoid 2, the relay can be set or adjusted to respond to an increase of one millampere in the circuit, or it can be 95 adjusted to operate at any other value, such as one ampere, or more, as the necessity or requirements may be to give a wider margin of inoperative current flux. It has also been found that it can be regulated to be inoperative over currents of greatly wider margin than this, even to the extent of exercising its control only upon the advent of excessively large current surges. 100

It will be evident to those skilled in the 105 art that the solenoids may be constructed from conductors of varying current carrying capacities and with or without a core member to provide magnetic fields of any desired strength or any desired ratio as the 110 application of the relay may necessitate.

Relays constructed in accordance with the invention may be adapted for a large variety of uses such as for use in the operation of control devices like alarms, signal lights, and 115 numerous other purposes. A particular application of a relay of this character is illustrated in Fig. 7 in connection with a power transmission system where it is utilized for recording unbalanced conditions, such as are 120 encountered by flash-overs of short duration or momentary breakdowns due to lightning or other causes in the distribution of current.

In Fig. 7, the three-phase transmission line is illustrated comprising three conductors 13, 14 and 15 connected to a neutral lead 16 which in turn is connected through the primary winding 17 of the transformer 18 to the ground. The secondary winding 19 of the transformer 18 is connected to a relay 130

constructed in accordance with the invention, indicated generally at 20, with the outer solenoid 1 and the inner solenoid 2 connected to the secondary winding 19 of the transformer in parallel circuit relation. The armature 5 of the relay in this application when drawn to the core member 4 moves the movable contact member 9 against the fixed contact member 11 to close an electric circuit through conductors 21 and 22 which may lead to a control device such as a circuit breaker located at any desired point. In this particular case, the relay may be adjusted so that when normal conditions prevail in the transmission line, the armature will not close the contacts to complete the circuit of which conductors 21 and 22 are a part. However, upon occurrence of a disturbance, such as an unbalanced condition, or a flash-over between any of the conductors of the transmission line, the current surge created thereby in passing through the relay will cause sufficient increase in flux density in the relay as controlled by the floating pole pieces 8 as to cause the armature to be immediately moved to a position to close the contact members 9 and 11, and complete the circuit which they control.

In view of the fact that the outer solenoid which in conjunction with the floating pole pieces act as a sort of valve for controlling the operation of the armature having a magnetic field substantially all in air, various fluctuations in the magnitude of the magnetic field created by this coil may occur with great rapidity. Consequently, the relay will be exceptionally quick to operate and it has been found, for example, that its contacts will close during a fraction of the initial alternation of a half-cycle of a sixty-cycle power system.

It has also been found that by disposing the movable pole pieces 8 in various positions in the magnetic field of the solenoid 1, their influence upon the armature 5 can be so adjusted as to retard the rapid action of the armature due to the change in effect thereon as it moves from one position to another.

The wide range of applicability of the relay, both with very small and very heavy currents, together with its selectivity to be operated under wide or narrow ranges of both large and small currents is of great importance. The combination with a solenoid adapted to carry heavy currents continuously, of a solenoid of relatively high resistance capable of carrying a wide range of low currents continuously, and an armature with means for delicately adjusting and varying the magnetic fields provided by the solenoids upon the armature, provides a relay which combines simple and durable construction with great utility and applicability.

According to the provisions of the patent statutes, we have explained the principle and

mode of operation of our invention, and have illustrated and described what we consider to be its best embodiments. However, we desire to have it understood that, within the scope of the appended claims, the invention may be practiced otherwise than as specifically illustrated and described.

We claim as our invention:

1. In an electro-magnet comprising a plurality of solenoids concentrically mounted one within the other, an armature disposed to be actuated by the magnetic flux surrounding said solenoids, and permeable means adapted to be adjusted to vary the amount of magnetic flux affecting the armature.

2. In an electro-magnet comprising a pair of magnetic coils concentrically mounted one within the other, a movably mounted armature interposed between said coils and a permeable member adapted to be adjusted to different positions in relation to said armature and said coils to vary the effect upon the armature of the magnetic flux surrounding said coils.

3. In an electric relay, the combination of an inner and an outer concentric radially spaced solenoid, a core disposed coaxially within said inner solenoid, an armature mounted for movement in response to energization of said solenoids, and means for adjustably varying the effect of the magnetic flux surrounding the outer solenoid upon the armature.

4. In an electric relay the combination of an inner and an outer concentric radially spaced solenoid, a core disposed coaxially within said inner solenoid and an armature mounted for movement in response to energization of said solenoids, means for biasing said armature to a predetermined position, and means for adjustably varying the effect of the magnetic flux surrounding the outer solenoid upon the armature to predetermine the operation of said armature.

5. In an electric relay the combination of an inner and an outer concentric radially spaced solenoid, an armature mounted for movement in response to energization of said solenoids, and a permeable member movably mounted for varying the effect upon the armature of the magnetic flux surrounding the outer solenoid.

6. In an electric relay the combination of an inner and an outer concentric radially spaced solenoid, an armature pivotally mounted for movement in response to the magnetic field surrounding said solenoids when energized, and a plurality of permeable members movably mounted and adapted to vary the effect upon the armature of the magnetic field surrounding the outer solenoid.

7. In an electric relay the combination of an inner solenoid mounted upon a permeable core, an armature mounted for movement in response to the magnetic flux surrounding

- said solenoid when energized, an outer solenoid mounted coaxially with said inner solenoid and spaced therefrom so that the magnetic flux surrounding said outer solenoid 5 when energized normally will not affect the armature, and means for adjustably superimposing different amounts of the magnetic flux surrounding said outer solenoid upon the magnetic field of said inner solenoid to effect the movement of the armature.
8. In an electro-magnet the combination of a plurality of solenoids disposed to have overlapping magnetic fields, a movable armature mounted in a way to be actuated by the magnetic flux surrounding said solenoids, and a movably mounted member having high magnetic permeability characteristics for changing the flux density of the magnetic fields affecting the armature.
- 20 9. In an electric relay the combination of an outer and an inner solenoid, a permeable core member disposed in a fixed position within said inner solenoid, an armature mounted for movement in response to the energization 25 of said solenoids, the outer solenoid being spaced so that normally its magnetic field does not materially affect the movement of the armature and a movable pole piece adapted to influence a portion of the magnetic flux surrounding the outer solenoid to affect said armature, and means for predetermining the magnetic effort of said solenoids necessary to move said armature.
- 30 10. In combination with an electrical circuit to be controlled, a movable circuit controlling element, means for actuating said movable circuit controlling element comprising a plurality of windings that carry current varying in the same sense as the current 35 in the circuit to be controlled, and means mechanically independent of said movable element but associated therewith and with said windings whereby the torque exerted on said movable element can be varied to different amounts without necessitating current changes in the circuit to be controlled.
- 40 11. In combination with an electrical circuit to be controlled, a movable circuit controlling element, means for actuating said 45 movable controlling element comprising a plurality of windings carrying different values of current but varying in the same sense as the current in the circuit to be controlled, means mechanically independent of said movable element for varying the torque exerted on said movable element without affecting the current in the windings, and means for predetermining the torque necessary to effect movement of the movable element.
- 55 12. An electro-magnetic circuit controlling device comprising a movable circuit controlling element and means for causing movement of said element on the occurrence in the circuit to be controlled of current changes of a predetermined character, said means comprising a plurality of concentrically spaced windings that carry current of different values varying in the same sense as the current in the circuit to be controlled, and mechanically independent permeable means for varying the torque exerted on the movable member independently of the current in the windings, and resilient means for predetermining the torque necessary to effect movement of the movable element.
- 70 13. In an electro-magnetic device comprising two concentrically spaced windings, an armature pivotally disposed longitudinally between the windings, and means for varying the magnetic torque exerted upon the armature.
- 75 14. An electro-magnetic device comprising in combination a solenoid, an armature mounted for movement transverse to the axis of the solenoid and in response to the current conditions therein, and adjustable permeable means for varying the effect upon the armature of the magnetic flux surrounding the solenoid.
- 80 15. An electro-magnetic device comprising in combination a solenoid of substantial diameter, a permeable core concentrically mounted longitudinally within said solenoid, an armature mounted for movement transverse to the axis of said core and solenoid and in response to the current conditions in the latter, and adjustable permeable members for varying the effect upon the armature of the magnetic flux surrounding the solenoid.
- 85 16. An electro-magnetic device comprising a solenoid having a substantial diameter, an armature mounted inside of said solenoid and arranged for movement transverse to the longitudinal axis of and in response to the changes in magnetic field there-within, and means for biasing said armature away from the longitudinal axis of the solenoid.
- 90 17. An electro-magnetic device comprising a solenoid having a substantial diameter, a permeable core longitudinally disposed within said solenoid, an armature also mounted within said solenoid and arranged for movement transverse to the longitudinal axis of said core and in response to variations in the magnetic field in the solenoid, and means biasing said armature away from the longitudinal center of said core.
